UNITED STATES PATENT OFFICE.

ARTHUR S. LANG AND RUPERT C. P. LANG, OF FALL RIVER,
MASSACHUSETTS.

RING-RAIL FOR SPINNING-FRAMES.

SPECIFICATION forming part of Letters Patent No. 424,215, dated March 25, 1890.

Application filed November 1, 1889. Serial No. 328,908. (No model.)

To all whom it may concern:

Be it known that we, ARTHUR S. LANG and RUPERT C. P. LANG, both of Fall River, in the county of Bristol, State of Massachusetts, have 5 invented certain new and useful Improvements in Ring-Rails for Spinning-Frames, of which the following is a description sufficiently full, clear, and exact to enable any person skilled in the art or science to which said 10 invention appertains to make and use the same, reference being had to the accompanying drawings, forming part of this specification, in which—

Figure 1 is a top view of a fragment of our 15 improved rail, showing some of the rings in position; Figs. 2 and 3, sectional elevations of the same, showing method of attaching the supporting-rods; Fig. 4, a plan of a portion of a side bar, showing the ring-socket; and Fig. 20 5, a vertical transverse section of the same.

Like letters and figures of reference indicate corresponding parts in the different figures of the drawings.

Our invention relates especially to means 25 for securing rings in the rail of a spinning-frame; and it consists in certain novel features hereinafter fully set forth and claimed, the object being to produce a simpler, cheaper, and more effective device of this character 30 than is now in ordinary use.

The nature and operation of the improvement will be readily understood by all conversant with such matters from the following explanation:

35 In the drawings, A represents the supporting-rods of the rail, B the rings, and C the side bars. The rings are of the ordinary construction and provided with peripheral flanges b in the usual manner. The side bars C are 40 preferably rectangular in cross-section. At suitable intervals the bars C are provided with curved or segmental undercut recesses f in the upper portion of their adjacent edges, as best shown in Figs. 4 and 5. These recesses are adapted to receive and retain a

45 flange b of the rings. The side bars are secured together by laterally-arranged screw-bolts g, passing through suitable openings in one rail, preferably countersunk to conceal 50 the heads of said bolts, and having their

threaded ends h turned into correspondingly-threaded openings in the opposite bar. The rings are disposed in the usual position in corresponding recesses f of the bars C, and the bolts g are then set up, securely clamping 55 said rings in position. The recesses being undercut, as described, the flanges b entering therein prevent accidental vertical movement of said rings.

The lifting or supporting rods A have their 60 upper ends threaded at m, and a U-shaped or forked head p is turned thereon, the arms of said head being inserted in proper openings in the under face of the side bars C, as best shown in Fig. 2.

65 The shape of the heads permits a slight spring action thereto and prevents them from interfering with the proper clamping of the rings in the side bars.

Having thus explained our invention, what 70 we claim is—

1. A ring-rail for spinning-frames, comprising side bars provided with segmental recesses in their adjacent edges, and screw-bolts for clamping the rings therein, substantially as described. 75

2. In a ring-rail, side bars secured together by screw-bolts and provided in adjacent edges with segmental undercut recesses adapted to receive the ring-flange, substantially as described. 80

3. In a ring-rail, side bars connected by screw-bolts and provided in adjacent edges with segmental undercut recesses, in combination with supporting-rods having detachable forked heads adapted to be inserted in sockets in the rail, substantially as and for the purpose set forth. 85

4. In a ring-rail, rectangular side bars having segmental undercut recesses in their adjacent upper edges for receiving the ring-flange, screw-threaded lifting-rods, and U-shaped heads thereon having their arms disposed in sockets in said bars, substantially as described. 90

5. In a ring-rail, the combination of rectangular side bars connected by screw-bolts and provided with segmental undercut recesses in their adjacent edges, flanged rings disposed in said recesses, screw-threaded sup- 95 100

porting-rods, and forked heads turned into said rods, their arms being disposed in sockets in said side bars, substantially as described.

6. In a ring-rail, the side bars C, provided with the recesses f, in combination with the bolts g, connecting said bars, substantially as described.

7. In a ring-rail, the side bars C, provided with the recesses f, and connected by bolts g,

in combination with the rods A, provided with detachable forked heads p, and the rings B, disposed in said recesses, substantially as and for the purpose set forth.
